DEVICE FOR DETERMINING FINGER-HOLE POSITIONS IN A BOWLING BALL

Robert E. Moreo, Fraser, Mich., assignor to Stowe-Woodward, Inc., Newton Upper Falls, Mass., a corporation of Massachusetts

Filed May 17, 1965, Ser. No. 456,235
2 Claims. (Cl. 33—174)

The present invention relates to the drilling of finger-holes in bowling balls and, more particularly, to the provision of such finger-holes in conformity with the particular dimensions of the hand of the individual bowler. Although the casual bowler may be satisfied to choose the most comfortably handled among pre-drilled bowling balls that may be available on a particular occasion, the serious or professional bowler often finds it advantageous to use a ball, the finger-holes of which have been particularly fitted to his hand. The present invention contemplates a novel device by which finger-hole sizes and spacings of very wide range may be adjusted to provide either a left handed or right handed bowler with the precise feel that he will experience when a bowling ball is drilled to corresponding specifications.

The primary object of the present invention is to provide a novel device of the foregoing type in the form of a ball-like configuration having a construction that simply and efficaciously enables the selection of the size of the thumb-hole, the sizes of and spacing between the middle-finger and ring-finger holes and the distance between the thumb-hole and the middle-finger and ring-finger holes for both left and right handed bowlers in a device of relatively few parts. Essentially, the ball-like configuration comprises a medial body section presenting a generally spherical periphery about an axis and opposed hollow regions through which the axis projects, and a pair of opposed sector cap sections presenting oppositely convex spherical surfaces, which cap sections are pivotally attached to the body section in such a way that their outer spherical surfaces continue the outer spherical surface of the body section. The body section is provided with a sequence of paired ring-finger and middle finger holes. The two different cap sections are provided with two different sequences of thumb-holes, the thumb holes of each sequence being of different diameter. The arrangement is such that the cap sections are readily interchangeable so that a variety of different relationships peculiar to the hands of right handed and left handed bowlers can be achieved.

Other objects of the present invention will in part be obvious and will in part appear hereinafter.

The invention accordingly comprises the device possessing the features, properties and relation of parts, which are exemplified in the following detailed disclosure, the scope of which will be indicated in the appended claims.

For a fuller understanding of the nature and objects of the present invention, reference should be had to the following detailed description, taken in connection with the accompanying drawings, wherein:

FIG. 1 is a perspective view of a preferred device embodying the present invention;

FIG. 2 is a cross-sectional view of the medial body section of the illustrated device taken midway between its axial extremities in the plane 2—2 of FIGURE 3;

FIG. 3 is a side elevation, partly broken away, of the medial body section;

FIG. 4 is a side elevation, partly broken away, of one of the opposed sector cap sections of the illustrated device;

2

FIG. 5 is a top plan view of one of the sector cap sections; and

FIG. 6 is a top plan view of the other of the opposed sector cap sections.

5 The device disclosed specifically herein as embodying the present invention is most generally shown in FIG. 1 as including a medial body section 10 and a pair of opposed cap sections 12 and 14. The outer peripheries of all sections 10, 12 and 14 present a spherical surface except for sequences of differently dimensioned holes in the sections and variable gaps between the sections. The sequence of holes in the medial body section is in the form of pairs 16, 18 of smaller and larger holes that are designed to selectively fit the ring and middle fingers of a bowler. The sequence of holes 20 in one of the cap sections is designed to selectively fit the thumb of a right handed bowler when his ring and middle fingers are fitted to a pair of holes 16, 18 in medial body section 10. The sequence of holes 22 in the other of the cap sections is designed to selectively fit the thumb of a left handed bowler when his ring and middle fingers are fitted to a pair of holes 16, 18 in the medial body section. In a manner to be described below, the variable gaps between the sections provide clearance for pivotal movement of 15 the cap sections with respect to the body section in order to adjust the span between a selected ring and middle finger hole pair and a selected thumb hole. In a manner to be described below, holes 20 and 22 all are of different diameters and cap sections 12 and 14 are interchangeable 20 so that the wide variety of thumbhole sizes available on both cap sections 12 and 14 are available to both right handed and left handed bowlers. Thus, a right handed bowler will insert his thumb into a selected thumb hole 20 and his ring and middle fingers into a selected 25 pair 16, 18 of ring finger and middle finger holes. On the other hand, should a left handed bowler wish to utilize a selected thumb hole 20 available only on cap section 12, the cap sections would have to be interchanged in order to permit this bowler to insert his middle and ring fingers into selected pair 16, 18 of ring finger and middle finger holes. The arrangement is such that all of the ring finger, middle finger, and thumb holes are of regulation depth and such that spans between 30 ring fingers and middle finger pairs at one position and selected thumb holes at another position may be selected with great versatility notwithstanding the fact that available peripheral surface space is rigidly restricted by 35 official regulations.

As shown in FIGS. 2 and 3, medial section 10 is composed of hard rubber in an oblate shape which is developed about an axis through its center 23. Circularly enveloping the axis is a ridge 24, the most outward surface of which is spherical in conformation. Oppositely extending from ridge 24 are a pair of opposed indented spherical zones 26, 28 which are developed about center 23. At opposite axial regions of medial section 10 are a pair of opposed dished-out spaces 30, 32. Each space 30, 32 has an inwardly converging conical surface 34 that intersects depressed spherical surface 26 or 28 and that is inwardly limited by 40 an inner circular surface 36 of a central hub 38. Hub 38 is integral with the remainder of medial section 10. Hub 38 is provided with opposed central bores, one of which is shown at 40, and a pair of opposed internally threaded shoulders, one of which is shown at 42, each 45 internally threaded shoulder 42 being more outward than each central bore 40. Turned into threaded shoulder 42 at each of faces 36, 36 is an externally threaded retaining disk 44, which is provided with a downwardly converging frusto-conical bore hole 46. Extending through bore hole 46 is the smaller diameter extension of a larger diameter shaft 48. At the inner extremity of the neck is a ball 50

which is seated in bore 40 and retained by disk 44. It will be apparent that shaft 48, by virtue of the foregoing structure, is universally pivotal.

Each of successive pairs of holes 16, 18 have parallel axes. In reference to FIG. 2, the successive pairs are characterized by successively different diameters. Specifically as shown in FIG. 2, the following holes are characterized by the following numbered diameters: #50— $2\frac{3}{32}$ inch; #52— $2\frac{5}{32}$ inch; #54— $\frac{1}{16}$ inch; #56— $\frac{3}{4}$ inch; #58— $2\frac{1}{32}$ inch; #60— $2\frac{3}{32}$ inch; #62— $\frac{5}{8}$ inch; #64— $1\frac{1}{16}$ inch; #66— $2\frac{5}{32}$ inch; #68— $3\frac{1}{32}$ inch; #70— $\frac{7}{8}$ inch; #72— $1\frac{15}{16}$ inch; #74— $2\frac{7}{32}$ inch; #76— $2\frac{9}{32}$ inch; #74— $2\frac{7}{32}$ inch; #76— $2\frac{9}{32}$ inch; #80— $1\frac{1}{16}$ inch; and #82— $\frac{7}{8}$ inch.

Each of cap sectors 12, 14 is in the form shown in FIG. 4 as being composed of hard rubber and having an exterior surface of spherical conformation 90, a shank 92 that is tapered inwardly and that presents a frusto-conical surface 94 and a limited internal spherical surface 96. The thickness between outer spherical surface 90 and inner spherical surface 96 is approximately the same as the distance between ridged spherical surface 24 and indented spherical surface 26 of medial section 10. The outer extremity of hub 92 is provided with a hollow bore 98 about the axis of the cap sector. Hollow bore 98 communicates with a hollow bore 100 that extends all the way through shank 92. It will be appreciated that hollow bore 100 receives a shaft 48 when inner spherical surface 96 bears against indented spherical surface 26 or 28 of medial sector 10. At any pivotal position of cap section 12 or 14 with respect to medial section 10, the cap section may be clamped into fixed position by the action of a wing nut 102 which as shown in FIG. 1, is turned onto the externally threaded extremity of its corresponding shaft into seated position against the inner extremity of hollow bore 98.

In reference to FIGS. 5 and 6, the successive thumb holes are characterized by different diameters. Specifically, as shown in FIGS. 5 and 6, the following holes are characterized by the following numbered diameters: #104— $2\frac{5}{32}$ inch; #106— $\frac{3}{4}$ inch; #108— $1\frac{3}{32}$ inch; #110— $1\frac{1}{16}$ inch; #112— $2\frac{7}{32}$ inch; #114— $1\frac{1}{16}$ inch; #116— $2\frac{9}{32}$ inch; #118— $\frac{5}{16}$; #120— $3\frac{1}{32}$ inch; #122—1 inch; #124— $1\frac{1}{32}$ inch; and #126— $\frac{7}{8}$ inch.

In operation, first that cap section 12 or 14, which presents the particular thumb hole suited to the hand of the bowler being measured, is positioned at one or the other of the regions of body section 10 depending on whether the bowler is right or left handed. Next, the other cap section is positioned at the remaining region of body section 10, with associated shaft 48 projecting through bore hole 100 and wing nut 102 turned into its innermost clamping condition. Next the bowler selects the ring finger and middle finger hole pair 16, 18 that most closely fits his fingers. Then the bowler pivots and rotates the selected cap section with respect to the body section into the most comfortable relative position. Finally, the wing nut 102 of the selected cap section is turned into its innermost clamping condition.

The present invention thus provides a versatile device for providing a bowler with the precise feel of a ball that is to be drilled. Since certain changes may be made in the above description and drawings without departing from the scope of the invention above disclosed, it is intended that all matter described in the foregoing specifica-

tion and illustrated in the accompanying drawings be interpreted in an illustrative and not in a limiting sense.

What is claimed is:

1. A device for measuring bowling grip, said device comprising a medial body section and a pair of opposed cap sections that pivotable and rotatable with respect to said medial body section, said medial body section presenting an outer spherical surface and a pair of inner spherical surfaces on opposite sides of said ridge spherical surface, each of said opposed cap sections including an outer spherical surface and an inner spherical surface, the distance between the outer spherical surface of said body section being approximately equal to the distance between the outer spherical surface of said cap section and the inner spherical surface of said cap section, said body section including a hub portion extending therewithin generally perpendicularly with respect to an axis about which said outer spherical surface of said body section is developed, a pair of opposed rods, one of said opposed rods having its inner extremity universally pivoted in said hub portion and its outer extremity threaded and extending roughly along said axis in one direction, the other of said opposed rods having its inner extremity universally pivoted in said hub portion and its outer extremity threaded and extending roughly along said axis in the other direction, said cap sections having axial bores receiving said rods, the inner spherical surfaces of said cap sections being seated on the outer spherical surfaces of said body section, threaded nuts turned onto the threaded outer extremities of said rods in order to clamp said cap sections against said body section, said cap sections being rotatable about said rods, the outer peripheral surfaces of said body section and said cap sections defining a continuous spherical surface except for holes in said cap sections and said body section and gaps between said cap sections and said body section, said holes including pairs of ring finger and middle finger holes in said outer spherical surface of said body section, one of the holes of each pair being of lesser diameter and the other of the holes of each pair being of greater diameter, the holes of different pairs being of different diameters, said holes including a sequence of thumb holes in one of said cap sections and a sequence of thumb holes in the other of said cap sections, the holes of each sequence being of different diameters, the holes of one sequence being of different diameters from the holes of the other sequence, said cap sections being removable from and interchangeable on said rods so that any selected hole of either cap section is available to receive the thumb of a right or left handed bowler when his middle and ring fingers are received in a selected pair of holes in the body section.
2. The device of claim 1 wherein said cap sections at the outer extremities of said axial bores being provided with depressions communicating with said axial bores, said threaded nuts being at least partially disposed in said depressions.
